UNITED STATES PATENT OFFICE.

LORNE A. COLE, OF BRANTFORD, ONTARIO, CANADA.

COIL-FORMING MACHINE.

Application filed April 10, 1925. Serial No. 22,146.

My invention relates to improvements in coil forming machines, and the object of the invention is to devise in a single machine means for both winding a loop and then spreading the same to form a D. C. armature or A. C. rotor or stator diamond coil, in which the time is economized when changing from the operation of winding to the operation of spreading, in which the coil when spread is in such a position as to permit of the easy application of the clips or tie wires usually employed for holding the coil conductors together before taping, and it consists essentially of the arrangement and construction of parts as hereinafter more particularly explained.

Fig. 1 is a perspective view of my machine shown in the winding position.

Fig. 2 is a similar view to Figure 1 showing the parts in the spreading position.

Fig. 3 is a similar view to Figure 2 showing the parts in the position they assume when spreading the loop to form the finished coil, but in the inverted position it assumes during the spreading operation.

Fig. 4 is a plan view of my machine.

Fig. 5 is a longitudinal sectional view on line 5—5 Figure 4 showing the parts in the loop winding position.

Fig. 6 is a longitudinal sectional detail on line 6—6 Figure 4 showing the parts in the loop winding position.

Fig. 7 is a similar view to Figure 6 showing the parts in the spreading position.

Fig. 8 is a transverse sectional view on line 8—8 Figure 4.

Fig. 9 is a cross sectional view on line 9—9 Figure 8.

Fig. 10 is a perspective detail of one of the winding jaws.

Fig. 11 is a detail in elevation of the wound loop.

Fig. 12 is a perspective detail of the loop spread to form the coil.

In the drawings like characters of reference indicate corresponding parts in each figure.

1 indicates a suitably driven shaft carrying the main supporting member 2 in the form of a bar, provided with a longitudinally extending open ended slot 3.

4 is a transverse bar member which is secured to the supporting member 2 at a point intermediately of its length by means of bolts 5 or other securing means. The member 4 is provided with longitudinal slots 4^x

and 4° extending from each side of the centre thereof.

Each jaw 6 and 7 comprises a bar portion 6^x provided with a longitudinally extending slot 6° and an upturned portion 6¹ extending from one end of the bar portion 6^x. Each of the jaws 6 and 7 are set in a stationary position by a bolt 8 extending down through each slot 4^x and 4°, and through the slot 6° of each jaw 6 and 7. By this means the jaws 6 and 7 may be adjusted either transversely of the machine according to the size of the coil or transversely of the supporting member 4 according to the thickness of the coil.

9 and 10 are a pair of rod members.

11 and 12 are blocks, each provided with an orifice 12^x through which a corresponding rod member 9 or 10 extends, being adjustably secured therein by means of a set screw 13.

The converging ends of the rod members 9 and 10 are provided with an inter-engaging tongue and jaw connection 14 through 80 which a pivot bolt 15 extends for connecting the parts together.

16 is a loop swung upon the pivot bolt 15 and to which is connected a tension spring 17, the opposite end of such spring being 85 connected to an eye 18 carried on the supporting member 2.

19 and 20 are rod members which extend freely through the blocks 11 and 12 to one side of the rods 9 and 10.

21 and 22 are blocks slidably carried upon the rods 19 and 20 in proximity to their opposite end.

23 and 24 are converging rods similar to the rods 9 and 10.

25 is a slide bar slidably held within the open ended slot of the supporting bar 2, so as to move longitudinally thereof. In order to support the bar 25 within the slot 3, I provide cross plates 26 and 27, each having 100 a centre opening 28.

29 is a transverse bar member also provided with longitudinal slots 30 and 31 extending from each side of its centre.

32 is a stem extending from the bar member 29 through the slide bar 25 and through the opening 28, and through the plate 27 as clearly indicated in Figure 5.

33 is a compression spring bearing at its lower end upon the plate 27 and secured in 110 position by means of the securing nut 34 which is threaded down upon the stem 32.

so as to adjust the compression of the spring 33.

35 is a stem extending from the slide bar 25 around which extends a compression 5 spring 36 bearing upon the plate 27 and adjusted by means of the adjusting nut 37 to vary the compression of the spring 36.

It will be understood that the plates 26 and 27 extend transversely of the slide bar 10 25, so as to bear on each side of such slide bar upon the stationary supporting bar 2, thereby forming a slidable connection, permitting the free sliding movement of the bar 25 within the slot 3.

15 38 is an eye carried by the slide bar 25, and 39 is a tension spring connected at one end to the eye 38 and at its opposite end to the converging ends of the rods 23 and 24, in a similar way to that described in connection with the spring 17 and rods 9 and 10.

20 40 and 41 are jaw members similar to the jaw members 6 and 7 and similarly carried in a stationary position upon the bar 29 and in an inverted position to the jaw members 25 6 and 7, the jaw members 6 and 7 gripping the lower side of the loop, and the jaw members 40 and 41 gripping the upper side of the loop as shown in Figure 2.

25 42 and 43 are bolts adjustably secured 30 within the slots 4^x and 4° the heads 42^x and 43^x of which form stops for limiting the outward movement of the rods 19 and 20, and parts carried thereby, which I will now describe.

35 Similar bolts are provided in the slots 30 and 31 of the bar 29.

40 44 and 45 are blocks set in a stationary position by set screws 46 respectively to the rods 19 and 20 so as to be adjusted according to the thickness of the coil.

45 47 and 48 are blocks also secured to the rods 19 and 20, the blocks 44 and 45 being spaced apart from the blocks 47 and 48 at a distance equal to the width of the loop which is to be wound around the rods 19 and 20 between the spaced apart blocks.

50 In order to hold the turns of the conductor within the jaws 6 and 7, I provide a piece of key stock 49 fitting the jaws 6 and 7, and a similar piece of key stock 50 fitting the jaws 40 and 41.

55 51 and 52 are clamping plates which are clamped down upon pieces of key stocks 49 and 50, to clamp them upon the turns of the loop. It will of course be understood that other means may be employed for securing these key stocks temporarily in place, and the means shown is only illustrative of one way of producing this result.

60 53 is a bar member secured at one end to the block 47 and passing freely in contact with the block 48.

65 59 is a plate adjustably secured by bolts 60 within the slotted opening 61 of the bar member 53, the plate 59 being provided with

upturned tongues 62 forming a receiving recess into which the block 48 fits during the winding operation. When the block 48 is held in this position a key plate 63 is passed down through the slotted openings of the bars 4 and 53 when one bar underlies the other in the position shown in Figure 5, the key being passed downward in a position longitudinally of these bars and then turned transversely to the bars, so that the slotted 70 out portions 64 engage the bars and lock them together in spaced apart locked relation and the blocks 48 positively between the tongues 62 of the plate 59 for a purpose which will hereinafter appear.

80 Having described the principal parts involved in my invention, I will briefly describe the operation of the same.

The first operation of my machine is to form a loop. During the winding operation 85 the parts assume the position shown in Figures 1, 5 and 6, that is the transverse bars 4 and 29 are in closely adjacent positions, the jaws 6 and 7 overlapping the jaws 40 and 41 so as to receive the upper and lower runs or sides of the loop. The blocks 11 and 12, 21 and 22 in which the rods 19 and 20 are slidably held are located directly to the outside of the transverse bars 4 and 29, the rod 20 being secured to the bar 53 and the rod 19 connected to such bar so that they move together in a direction longitudinally of the rod 19, the rod being free to move longitudinally of the bar member 53 as the parts assume the spreading position. The bar member 53 is located during the winding operation beneath the transverse member 4 as illustrated in Figure 5. The slide bar 25 is secured to the transverse member 29 and therefore they move together to 100 the spreading position with the rods 23 and 24 and the spring 39 connected thereto. The rods 9 and 10 and spring 17 are held in a stationary position during the movement of the parts to the spreading position. In starting the formation of the loop, the end of the lead wire or other member forming the loop is drawn from the reel and laid within the jaws 6 and 7. The key stock 49 is then inserted in these jaws in the position shown, and is clamped down so as to firmly hold the lead wire within the jaw during the initial turning movement. The shaft is then rotated one turn so that the wire is passed around the rods 19 and 20 and brought into 105 juxtaposition to the opposite end of the key stock and into the jaws 40 and 41. When thus wound it has sufficient frictional grip within the jaws to hold it in position during the remainder of the winding operation.

110 The key stock is therefore removed and the winding operation completed. After the winding operation has been completed, the key stocks 49 and 50 are inserted respectively in the jaws 6 and 7 and 40 and 41 115 120 125 130

and clamped down by means similar to that hereinbefore described so as to firmly secure the loop in place.

It will be understood from the above that in starting the winding operation only one key stock is inserted to hold the free end of the lead in the jaws 6 and 7. This key stock is left in place until nearly one turn is made, the lead wire then has sufficient grip to hold in place by frictional contact. The key is then removed and the winding operation completed. After the winding operation is completed both key stocks are inserted and the spreading operation is performed.

In order that the bar members 19 and 20 be held definitely in position during the winding operation, the plate 59 is adjusted upon the bar 53 and the block 48 inserted therein. By this means the block and consequently the rod 19 is held in a definite spaced apart relation to the rod 20. In order that the block be positively held in this position, the rod member 53 is secured to the bar member 4 by means of the key 63. It will thus be seen that the block 48 is secured by the plate 59, between the bar members 53 and 4.

It will thus be seen by this construction the rod members 19 and 20 are held and locked in definite spaced apart relation to form a loop of definite size. In order to vary the size of the loop, the plate 59 and the bolts 42^x and 43^x are adjusted transversely of the machine, thereby regulating the length of the loop. After the winding operation is completed, the locking key 63 is removed, the free end of the bar member 53 is then manually lifted so that the block 48 clears the projection 62, the tension in the loop draws the block 48 and parts connected therewith slightly inward out of alignment with the projection 62. The bar 25 is then manually drawn outward by any suitable means longitudinally of the slot 3.

It will thus be seen that by this movement the bar member 29 and jaws 40 and 41 are drawn outward carrying with them the corresponding portion of the loop, that portion of the loop held in the jaws 6 and 7 remaining stationary. As the bar member 29 is drawn outward it engages the blocks 21 and 22 carrying them outward upon the rods 19 and 20.

It will be readily understood that the ends of the loop passing between the blocks 47 and 44 and 48 and 45 are necessarily drawn outward in the direction of arrow, see Figure 3, by the movement of that portion of the loop held within the jaws 40 and 41. Simultaneously the rods 19 and 20 slide through the blocks 11 and 12. By referring particularly to Figure 3, it will be seen that the oppositely directed faces of the blocks 47 and 44, and the blocks 48 and 45

are flush with the periphery of the rods 19 and 20 just barely sufficient metal being left for forming the orifice.

By this means when the loop is spread, the ends of the loop incline outward in opposite directions over these block faces as clearly indicated in Figure 3, thereby spreading the loop in the form required to form the completed coil the sides of the loop assuming a position equi-distant from an imaginary centre line of the loop as indicated by the dash line x—x Figures 4, 11 and 12 and the ends of the loop drawing inward towards each other along this centre line to permit the spreading of the sides of the loop. Necessarily as the sides of the loop are drawn apart the ends remain centrally therebetween as there is nothing to make them assume any other position as the loop spreads and the ends drawn inward toward each other on the line x—x.

It will of course be understood that as this operation takes place, the longitudinal distance between the ends of the coil becomes reduced and consequently the rods 19 and 20 are gradually drawn together, exerting greater tension upon the springs 17 and 39, thereby keeping the tension on the ends of the loops as the loops are spread, so that the strands are held in their proper shape and relative position.

In order to remove the completed coil, the springs 39 and 17 are detached and the blocks 21, 22, 11, and 12, removed from the rods 19 and 20 carrying with them the rods 23 and 24, and 9 and 10. By this means the free removal of the rods 19 and 20, and the parts carried thereby is permitted, such rods being slipped inward of the machine, so as to clear the ends of the coil and enable them to be passed longitudinally outward from the coil. When this is done the coil is left in the jaws 6 and 7 and 40 and 41 clear of all mechanism, and thereby enables the easy application of the usual clips or tie wires to the coil. When the tie wires are applied, the key stock 50 is removed, the coil slipped from out of the jaws 40 and 41, the bar member 29 moved outward clear of the machine and then the key stock 49 is removed from the jaws 6 and 7 permitting the coil to be slipped out of these jaws completed.

What I claim as my invention is:

1. In a coil forming machine, a rotatable member, a loop forming device carried by the rotatable member, and on which a closed loop is formed having parallel sides, and comprising loop end forming and carrying members between which the parallel sides of the loop extend, a supporting structure adapted to resiliently hold the loop end carriers apart, and in which the carriers move freely transversely of the loop, means stationary in relation to the rotatable member and engaged by one longitudinal loop side

- at points spaced from the ends of the loop as the loop is formed, means movable in relation to the rotatable member laterally of the loop for engaging the other longitudinal 10 loop side at points also spaced from the ends of the loop, whereby by the outward movement of the movable member the loop sides are spread apart, and the ends drawn in a corresponding direction into alignment with 15 the longitudinal centre of the completed loop and towards each other against the aforesaid resilient holding means.
2. In a coil forming machine, a rotatable member, a loop forming device carried by the rotatable member, and on which a closed loop is formed having parallel sides, and comprising loop end forming and carrying members, means for maintaining a yieldable tension longitudinally of the loop, a supporting structure in which the carrying members are held to move transversely of the loop, means carried in a stationary position upon the rotatable member for engaging one longitudinal side of the loop, a transverse member also carried on the rotatable member and movable transversely of the loop, and gripping means carried by the stationary and movable members for engaging the sides of the loop. 20
3. In a coil forming machine, a rotatable member, a loop forming device carried by the rotatable member, and on which a closed loop is formed having parallel sides, and comprising loop end forming and carrying members, means for maintaining a yieldable tension longitudinally of the loop, a supporting structure in which the carrying members are held to move transversely of the loop, means carried in a stationary position upon the rotatable member for engaging one longitudinal side of the loop, a transverse member also carried on the rotatable member and movable transversely of the loop, gripping means carried by the stationary and movable members for engaging the sides of the loop, and means for locking the loop end carriers in their extreme spread apart position during the winding of the loop and removable during the spreading 30 operation.
4. In a coil forming machine, a rotatable member, a loop forming device carried by the rotatable member, and on which a closed loop is formed having parallel sides, and comprising loop end forming and carrying members, means for maintaining a yieldable tension longitudinally of the loop, a supporting structure in which the carrying members are held to move transversely of the loop, means carried in a stationary position upon the rotatable member for engaging one longitudinal side of the loop, a transverse member also carried on the rotatable member and movable transversely of the loop, gripping means carried by the stationary and movable members for engaging the sides of the loop, and means for locking the loop end carriers in their extreme spread apart position during the winding of the loop and removable during the spreading 40 operation.
5. In a coil forming machine, a rotatable member, a loop forming device carried by the rotatable member, and on which a closed loop is formed having parallel sides, and comprising loop end forming and carrying members, means for maintaining a yieldable tension longitudinally of the loop, a supporting structure in which the carrying members are held to move transversely of the loop, means carried in a stationary position upon the rotatable member for engaging one longitudinal side of the loop, a transverse member also carried on the rotatable member and movable transversely of the loop, gripping means carried by the stationary and movable members for engaging the sides of the loop, and adjustable means for locking the loop end carriers in their extreme spread apart position during the winding of the loop and removable during the spreading 50 operation.
6. In a coil forming machine, a rotatable member, a loop forming device carried by the rotatable member, and on which a closed loop is formed having parallel sides, and comprising loop end forming and carrying members, means for maintaining a yieldable tension longitudinally of the loop, a supporting structure in which the carrying members are held to move transversely of the loop, means carried in a stationary position upon the rotatable member for engaging one longitudinal side of the loop, a transverse member also carried on the rotatable member and movable transversely of the loop, gripping means carried by the stationary and movable members for engaging the sides of the loop, means for locking the loop end carriers in their extreme spread apart position during the winding of the loop and removable during the spreading operation, and adjustable means for limiting the spreading apart of the carriers. 60
7. In a coil forming machine, a rotatable shaft, a bar member extending from the shaft end in a longitudinal direction, a transverse bar member secured to the longitudinal member, a transverse bar member carried by the longitudinal member and movable longitudinally thereof from a position adjacent to the stationary bar member, hooked means carried by the stationary and movable bar members and overlapping each other so as to be in vertical alignment when the bar members are in an adjacent position and adapted to receive the upper and lower sides of the loop as it is wound, a supporting structure resiliently held from movement in 70

a vertical plane and located adjacent both to the stationary transverse member and to the movable transverse member, rod members located at each side of and parallel to the bar member of the shaft, blocks carried by each of the rod members in spaced apart position, and having their upper and lower faces flush with the corresponding portion of the rod member and between which blocks 5 and around the rod member, the ends of the loop are adapted to pass as it is wound and over the flush faces of which the sides adjacent to such ends are adapted to extend as the loop is drawn into the spread position, and means with which the movable transverse bar member engages to draw the rods in a corresponding direction as such transverse member is moved. 15

LORNE A. COLE.
